ROLLER SKATE BRAKE

Theodore R. Goettie, Wayne, Pa.

Application November 22, 1937, Serial No. 175,942

2 Claims. (Cl. 280—11.20)

This invention relates to a brake for roller skates and it consists in the constructions, arrangements and combinations herein described and claimed.

5 It is an object of the invention to provide a structure in which simultaneous braking action will be applied equally to each of the front and rear wheels of a skate.

10 It is also an object of the invention to provide a brake structure which may be readily installed upon skates now in use.

15 It is a still further object of the invention to provide means for manually applying the brakes and provide means for automatically releasing the same.

Additional objects, advantages and features of invention will be apparent from the following description considered in conjunction with the accompanying drawing, wherein

20 Figure 1 is a side elevation of a skate, partly in section, showing my brake applied.

Figure 2 is a fragmentary bottom plan view thereof.

Figure 3 is a perspective view of a guide member employed in the brake.

25 Figure 4 is a perspective view of one of the brake shoes.

Figure 5 is a plan view thereof.

Figure 6 is a front elevation of a pair of 30 skates equipped with the brakes and illustrating the operating means therefor.

There is illustrated in Figures 1 and 2 a skate 10 having front and rear bracket members 11 and 12 to which there is mounted a truck 13 by means of a bolt 14. The bracket 11 is carried by a forward section 15 extensibly connected with a rear section 16 associated with bracket 12, the sections being retained in adjusted position by means of bolts 17. The construction described is well understood in the art.

40 Upon each of the bolts 14 adjacent their inner ends there is resiliently mounted a brake shoe 18, the shoes being apertured for reception of the bolt, a helical spring 19 being interposed between the shoe and truck 13. The shoes 18 comprise oppositely disposed contact portions 20 for braking action against respective rollers 21 of the skate, and an upstanding offset apertured lug 22. The spring 19 functions to maintain the brake in released position yet movable to engage the wheels 45 for braking action as will be described.

45 A box-like guide 23 is fixed to the underside of the skate and preferably includes a tongue 24 of a thickness to pass between the extensible sections

15 and 16 and secured therebetween upon tightening of the bolts 17. The tongue 24 also includes a hook portion 25 adapted to engage the inner longitudinal edge of the section 16 of the skate. The guide 23 will be positioned upon the skate with the entrance opening 26 disposed toward the outside of the skate, the entrance and outlet edges of the guide being rolled to prevent chafing or excessive wear upon actuator straps 27 threaded there-through, as will be described.

5 The straps 27 extend downwardly from a belt 28 adapted to be fixed about the waist of the skater, the straps extending downwardly upon the outside of the legs. The straps have branched extensions 29 and 30, the latter being threaded 10 through the guide 23, the branch 29 being secured to the extension 22 of the rear brake 18, while the branch 30 is secured to the front brake extension 22.

15 In use, when a skater desires to slow down or stop, it is merely necessary to give an upward pull upon the straps 27. This will effect a pull upon the extensions 29 and 30, causing movement of the brake shoes 20 into contact with the rollers 21, thereby retarding rotation of the rollers. 20 When such action takes place, the springs 19 will be compressed, and with release of pull upon the straps, the springs will return the brakes to normal released position.

25 While I have described the invention specifically and shown a preferred construction in the drawing, this is by way of illustration only, and I consider as my own all such modifications as fairly fall within the scope of the appended 30 claims.

35 I claim:—

1. In a roller skate, having front and rear truck mounting brackets, a roller truck for each bracket, a bolt connecting respective brackets and trucks, a brake shoe loosely mounted upon the 40 bolts, said shoe having oppositely disposed roller contact portions, a helical spring on each bolt interposed between a portion of the truck and the brake shoe normally holding the brake shoes in released position, each of said brake shoes having 45 an upward offset extension, a guide housing upon the underside of the skate, a pull strap threaded through the guide and having connection with respective upward extensions of the brake shoe.

2. The structure of claim 1 in which the pull 50 strap includes an adjustable belt for attachment upon a skater.

THEODORE R. GOETTIE.
